Patented Mar. 3, 1970

216,750

COMBINED GRILL AND LIGHTING FIXTURE

Edward Klein, Wilmette, Ill., assignor to Lear Siegler, Inc.,
Santa Monica, Calif., a corporation of Delaware

Filed Apr. 3, 1969, Ser. No. 16,563

Term of patent 14 years

Int. Cl. D7—04; D26—02, 03
U.S. Cl. D81—10

FIG. 2

FIG. 1 is a front perspective view of a combined grill and lighting fixture showing my new design; and

FIG. 2 is a back perspective view of FIG. 1.

I claim:

The ornamental design for a combined grill and lighting fixture, as shown and described.
